CLAIM

The ornamental design for a painting tool as shown and described.

DESCRIPTION

FIG. 1 is a perspective view of a painting tool showing my new design;

FIG. 2 is a top plan view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken lines show portions of the painting tool that form no part of the claim design.
